UNITED STATES PATENT OFFICE

CHARLES H. FRANZ, JR., OF MILWAUKEE, WISCONSIN

LOOSE-LEAF BINDER

Application filed January 8, 1927. Serial No. 159,810.

This invention relates to loose leaf binders. Objects of this invention are to provide a very cheap form of loose leaf binder which has novel fastening means cooperating directly with the peculiar formation or structure of the binder to lock the leaf-receiving pins, and permit the unlocking of such pins only when one of the covers is opened out flat, such cover acting to lock the locking means itself 10 when in closed or partly closed position.

Embodiments of the invention are shown in the accompanying drawings in which:—

Figure 1 is a fragmentary view of one form 15 of the binder opened out;

Figure 2 is a transverse sectional view on the line 2—2 of Figure 1;

Figure 3 is a transverse sectional view on the line 3—3 of Figure 1;

Figure 4 is a view corresponding to Figure 1, showing a modified form of binder.

Referring to the drawings, it will be seen that the binder comprises a pair of covers 1 and 2 which are integrally joined by means of a back 3. Further, it is to be noted that the back is provided with folded portions 4 and 5 adjacent each cover, such folded portions forming in reality reenforced strips positioned just inwardly of the covers. These reenforced strips 4 and 5 are held together by means of rivets 6 and 7, as shown particularly in Figure 3. The strips obviously could be held in other ways in their folded condition but it is preferable to hold them by the rivets, as this materially cheapens the manufacture 30 of the device. Further, it is to be noted that the covers and back may be formed of very cheap material by means of this construction.

The lower of the strips or flaps 5 is provided with a plate 8 which is held by means 40 of the rivets 7 one of which is shown in Figure 3. This plate is provided with pins 9 whose headed ends project through openings in the upper strip 4. These headed ends are locked by means of a sliding plate 10 provided with notches for the reception of the reduced portion beneath such heads. Preferably, the notches have an enlarged portion 11 adjacent their outer side and a constricted portion 12 extending therefrom. The slide 10 is provided with slots 13 through which the

rivets 6 project, such rivets, therefore, serving not only to hold the upper flap or reenforcing strip 4 in its folded condition, but also holding the slide 10 and guiding it, as is apparent from Figure 1.

It is to be noted that the slide 10 has all portions thereof adapted for simultaneous rearward motion, as it is designed for a parallel motion of all parts; that is to say, it is adapted for a direct rearward sliding motion transverse of the strip 4. Further, it is to be noted from Figures 1, 2, and 3 that the slide 10 is held locked against motion when the cover is closed, and that it may be slid rearwardly only when the corresponding cover is opened 65 out.

In using the device, the perforated leaves 14 are received upon the pins 9, and the pins are passed through the flap 4 while the cover 2 is in the open position, as shown in Figure 70 2. Thereafter, the slide 10 is moved forwardly to lock the headed ends of the pins 9. The closing of the cover 2 then locks the slide against motion. Further, it is to be noted that the slide 10 can not be moved rearwardly 75 even if the cover is partly opened up. It can be moved rearwardly only when the cover is completely open, as shown in Figure 2.

Further, it is to be particularly noted that by having the slide moved transversely of 80 the strip, that it is impossible to inadvertently detach the device as is frequently the case with the slides which move longitudinally, as the projecting parts are frequently inadvertently caught and thus the slide is moved 85 to detaching or unlocking position. However, with this invention such inadvertent detachment of the slide is impossible, as it requires a deliberate and complete opening of the cover before the slide can be moved at 90 all, as all parts of the slide move directly rearwardly.

Figure 4 shows a modified form of the invention in which the covers 15 and 16 are integrally joined by means of a back, and 95 are provided with locking pins 18 similar to the locking pin 9 shown in Figure 2. However, two distinct slides 19 are provided for locking the headed ends of the pins. Otherwise the two forms of the device are the same. 100

It is to be noted also that in the practice of this invention very cheap forms of covers may be provided and that the entire device may be made with the utmost cheapness. 5 Consequently, this form of loose leaf binder can be manufactured and sold at a very low figure.

Although the device may be made very cheaply it is apparent from the description 10 of the operation given above, that the loose leaves are securely held in place and voluntarily detached by the operator.

Although the invention has been described in considerable detail, such description is intended as illustrative rather than limiting as 15 the invention may be variously embodied and as the scope of such invention is to be determined as claimed.

I claim:

20. A loose leaf binder comprising a pair of covers, a forwardly directed strip carried by each of said covers, a slide carried by one of said strips, and positioned adjacent the folded portion of the cover to retain the slide against 25 movement when the cover is closed or partly closed, means slidably holding said slide and passing through such strip, said strip also having an opening, a pin carried by the other of said strips and having a headed end passing through the opening of said first-mentioned strip and engaged by said slide, all portions of said slide adapted to be simultaneously moved directly across said strip 30 only when the corresponding cover is opened 35 out to its fullest extent.

In testimony that I claim the foregoing I have hereunto set my hand at Milwaukee, in the county of Milwaukee and State of Wisconsin.
